UNITED STATES PATENT OFFICE.

FRED L. JOHNSON, OF BINGHAMTON, NEW YORK, ASSIGNOR TO MID-EAST SPECIALTY COMPANY, INC., A CORPORATION OF NEW YORK.

BAG.

1,415,450.

Specification of Letters Patent. Patented May 9, 1922.

Application filed April 18, 1921. Serial No. 462,097.

To all whom it may concern:

Be it known that I, FRED L. JOHNSON, a citizen of the United States, residing at Binghamton, in the county of Broome and State 5 of New York, have invented certain new and useful Improvements in Bags; and I do declare the following to be a full, clear, and exact description of the invention, such as will enable others skilled in the art to which 10 it appertains to make and use the same.

This invention relates to an improved paper bag and one object of the invention is to provide a paper bag having an improved handle construction for permitting 15 the bag to be easily carried and to further permit the upper end portion of the bag to be reinforced and thus greatly strengthened and prevented from having any tendency to tear when the bag is carried.

20 Another object of the invention is to so construct this reinforcing and handle forming means that it will permit the bag to be folded in the usual manner into a compact mass when not in use.

25 This invention is illustrated in the accompanying drawing, wherein:

Figure 1 is a view showing the improved bag in a folded condition.

Figure 2 is a longitudinal sectional view 30 through the upper portion of the folded bag.

Figure 3 is a fragmentary transverse sectional view taken along the line 3—3 of Fig. 1.

Figure 4 is a perspective view of the improved bag ready for filling.

Figure 5 is a perspective view of a reinforcing sheet used in constructing the improved bag.

Figure 6 is a plan view of a covering used 40 in constructing the improved bag.

Figures 7, 8 and 9 are vertical sectional views through the upper end portions of bags having modified constructions.

This bag 1 has opposed sides provided adjacent their upper ends or in other words adjacent the open end of the bag with openings 2 for receiving the fingers and it will thus be seen that when the bag is filled, the side portions may be brought together and the fingers 45 passed through these hand openings 2 so that the side portions of the bag may be grasped by taking hold of the cross bars 3 formed by these openings 2. As previously stated, it is desired to reinforce the sides of the bag 50 having the openings 2 formed therein and

in order to do so, a sheet 4 such as shown in Fig. 5 will be placed against the inner face of each side, as shown in Fig. 3. This sheet 4 will be formed of a relatively heavy or tough material and in the preferred form 60 will be formed of cardboard. This reinforcing sheet is provided with an opening 5 for registering with the opening 3 of the sides of the bag against which the sheet is secured.

A covering which is preferably formed of the 65 same type of material as the bag 1, is provided and this covering which is indicated by the numeral 6 will be formed from a blank

7 shown in Fig. 6. This blank 7 is provided with openings 8 in its end portion to register 70 with the registering openings 2 and 5 and this blank will be folded along the dotted lines 9 thus providing wings 10 which will extend upon opposite sides of the side portion of the bag when the covering is placed to 75 straddle the side portion of the bag. From an inspection of Fig. 3, it will be seen that this covering straddles the side portion of the bag and the reinforcing sheet 4 and further it will be seen from an inspection of Figs. 80

5 and 6, that the reinforcing sheet 4 is of approximately the same size and shape of one end portion of the blank 7 from the dotted line 9 to the ends of the frame. Therefore,

when the reinforcing sheet is put in 85 place and the covering put in place, the end portions of the covering which extend down along the inner and outer sides of the bag will correspond to the size and shape of the reinforcement 4. This will cause the upper 90 end portions of the sides of the bag to be greatly reinforced and strengthened and not only provide a bag which can be easily carried without danger of the handle portion

tearing, but will further provide a bag in 95 which the side portions will be strengthened and reinforced for a relatively large area and be prevented from having any tendency to be twisted and torn.

When the bag is not in use, it can be folded as shown in Fig. 1 100 and will thus be reduced to a flat mass which can be put away in a small amount of space.

While it has been stated that the bag is formed of paper, it is to be understood that it may be formed of canvas, cloth, leather 105 or any other suitable material, the covering being preferably formed of the same material and the reinforcement of more rigid material.

In the modified form disclosed, there has been shown other specific ways in which the 110

improved bag may be constructed. From an inspection of Fig. 7, it will be seen that if desired, the reinforcement sheet 4 may be placed against the outer face of the side 5 wall of the bag instead of being glued to the inner face as shown in Fig. 3. In this form, the covering will have the same construction as disclosed in Figs. 3, 4 and 6 and will be secured with one leaf positioned 10 within the bag and the second outside thereof. It will thus be seen that the only difference between this form and that shown in Fig. 3, is the fact that in the form shown in Fig. 3, the reinforcing strips or plates 4 15 are secured to the inner faces of the side walls of the bag whereas in this form, they are secured to the outer faces.

In the form shown in Fig. 8, the covering will be done away with and a reinforcing 20 sheet or strengthening sheet or plate 4 will be secured to the side wall of the bag and preferably against the inner face thereof. The strengthening sheet will be secured with the wall of the bag extending slightly above 25 the upper edge of the strengthening sheet and this extended portion of the wall of the bag will be turned in as shown at 11 and pasted to the upper edge portion of the strengthening sheet.

30 Another modified construction is shown in Fig. 9. In this form, the strengthening sheet 4 is done away with and instead of providing a strengthening sheet, the covering sheet of Fig. 6 will be put in place and 35 glued or otherwise secured to the inner and outer faces of the side walls of the bag. This form would be used in connection with a bag formed of a relatively heavy material not liable to readily tear, and it is mainly 40 desired to provide a hand grip so that the bag can be easily carried. If desired, means may be provided for releasably holding the mouth portion of the bag in a closed position. Fasteners 12 will be provided near

the mouth of the bag. In the present illustration, studs and sockets have been shown, but it is to be understood that other fasteners of a conventional construction could be used if so desired. It will thus be seen that this improved bag may be formed in 45 various ways but that in all cases, there has been provided a bag having opposed walls provided with openings through which the fingers may pass and that means has been provided for strengthening the portion of 50 the bag in which the openings are made thus preventing danger of the bag tearing when carried and further permitting it to be easily carried.

55 I claim:

1. The combination with a bag having its sides provided with a finger receiving opening adjacent the open mouth of the bag, of reinforcing means for the said side of the bag, the reinforcing means comprising a 60 sheet of relatively tough material fitting against one face of the side of the bag and provided with an opening registering with the opening of the side of the bag, and a separate cover element straddling the side 65 of the bag and having its side wings provided with openings registering with the openings in the sheet and side of the bag.

2. A bag having a hand opening in its side adjacent the open end of the bag, a 70 reinforcing sheet for the said side of the bag reinforcing the side about the opening therein, and a separate covering element straddling the said side of the bag and having its inner and outer side portions of substantially 75 the same size and shape as the reinforcing sheet, the reinforcing sheet and side portions of the covering being relatively 80 large and having openings registering with the opening in the side of the bag.

85 In testimony whereof I have hereunto set my hand.

FRED L. JOHNSON.
